PROCESSING MACHINE

Thomas H. Curtis, Red Bank, N. J., assignor to
 Hansen-Van Winkle-Munning Company, Mat-
 awan, N. J., a corporation of New Jersey

Application April 18, 1950, Serial No. 156,627

18 Claims. (Cl. 198—19)

1
 This invention relates to processing machinery, particularly to machinery for automatically, chemically or electrolytically treating work pieces.

In my co-pending applications, Ser. No. 92,838, filed May 12, 1949, now Patent 2,626,621, issued January 27, 1953, Ser. No. 154,077, filed April 5, 1950, and Ser. No. 156,626, filed April 18, 1950, now Patent 2,605,882, issued August 5, 1952, there is disclosed an automatic processing machine and a method of operation thereof in which different groups of workpieces can be given different types of treatment in one and the same machine without any modification in the machine set-up. The need for this type of treatment is set forth in those applications but may be treated briefly as follows.

In many instances where workpieces are being plated, it is desired that some of the pieces be plated more heavily than others. For example, in connection with automobile hardware, the interior hardware need not be as heavily plated as the outside hardware because it is not exposed to the same weather conditions. The plating on both of these types of workpieces is, however, the same type. It has been found that satisfactory results can be obtained only by plating within relatively narrow limits of plating conditions such as temperature of the bath, bath composition, current density, etc. Because of this, when a machine is set up to give the desired heavy plating on some of the workpieces, it is ordinarily not capable of applying the lighter plating to the other workpieces. It is not practical to interrupt the plating cycle on the workpieces to receive the light plate by cutting off the plating current while the workpieces are in the plating bath because this materially detracts from the quality of finish which results.

In still other circumstances it may be desired to run different groups of workpieces through a processing machine and to subject the different groups to treatment in different baths and for different periods. The usual type automatic processing machine is not capable of providing a selective treatment for different batches of workpieces because it is inflexible and is constructed to carry out only a single type of work cycle at a time.

In the first filed of the above applications, I disclosed certain manners for causing different batches of workpieces being conveyed through a processing machine to be selectively treated. The present invention is a further extension of the inventive thought embodied in that application

2

and includes different embodiments for obtaining the selective treatment of different batches of workpieces in a processing machine.

Accordingly, one of the principal objects of this invention is the provision of mechanism associated with a processing machine which is selectively adjustable to provide for different treatment cycles of different batches of workpieces.

A still further object is a provision of relatively simple mechanisms for inclusion in a processing machine of the automatic type which are operable independently of the operation of the processing machine to provide for selective treatment of different groups of workpieces passing through the machine.

A particular object of this invention is the provision of arrangements for lifting and lowering workpiece supporting members in a processing machine so that the workpieces on the members can selectively be given a reduced time treatment at any position about the machine if so desired.

These and other objects and advantages will become more apparent upon reference to the following description taken in connection with the accompanying drawings in which:

Figure 1 is a view showing a portion of a processing machine and a device incorporated therein according to this invention.

Figure 2 is a view looking in from the left side of Figure 1 and showing somewhat more in detail the arrangement of the device of this invention and the manner in which it cooperates with the workpiece supporting arm of the processing machine and the processing machine elevator.

Figure 3 is a view indicated by the line 3—3 on Figure 1 and showing an over-running clutch which is positioned between the drive motor for the device of this invention and the actuating chain.

Figure 4 is a wiring diagram showing the electric circuit components by means of which the action of the device is automatically obtained.

Figure 5 is a perspective view showing a part of one of the workpiece supporting arms and a cam arrangement therefor for cooperating with limit switches included in the circuit of Figure 4 to determine the cycle of operation of the device of Figures 1 and 2.

Figure 6 is a view showing a modified arrangement of the device wherein a hydraulic medium is employed for controlling the movement of the device.

Figure 7 is a view of still another modification

of the device wherein a lead screw is employed for raising and lowering the device instead of a chain.

Figure 8 is a sectional view taken on line 8-8 of Figure 7.

Figure 9 is a sectional view indicated by line 9-9 on Figure 8 and showing an over-running clutch arrangement associated with one of the worm wheels that runs on the lead screw that actuates the device.

Figures 10 and 11 are side and front views, respectively, of an early lift-out arrangement constructed similarly to the modification of Figures 1 through 5.

Figure 12 is a diagrammatic view of a control circuit for controlling the operation of the embodiment of Figures 10 and 11.

Figure 13 is a diagrammatic view showing how the hydraulic device of Figure 6 can be adapted for an early lift out of the workpiece carriers.

Figure 14 is a diagrammatic view showing how the various devices of this application can be controlled by photocell system instead of by the limit switches actuated by the carrier arms.

Modification of Figures 1-5

Referring to the drawings somewhat more in detail, in Figures 1 and 2 there is shown a portion of a processing machine which is substantially identical with that disclosed in my co-pending application Ser. No. 154,077 and my Patents 2,605,882 and 2,626,621, referred to above, with respect to the arrangement of the frame of the machine, the tanks therefor, the conveyor chains, the elevator, and the drive means for the elevator and conveyor chains. In Figures 1 and 2 the frame of the machine is indicated at 10 and comprises a lower channel 12 which receives conveyor chain 14 and an upper channel 16 that receives conveyor chain 18.

Extending between chains 14 and 18 at spaced intervals are the vertically extending frame parts 20 which form a track for receiving the skate-like element 22 that has rollers 24 engaging frame 20 for vertical movement of the said element.

Element 22 provides a support for a workpiece supporting arm 26 that extends outwardly over the tanks in which the several baths associated with the process are placed.

Extending rearwardly from element 22 is a pick-up roller 28 and this is adapted for engagement by angle 30 carried on elevator 32 so that when the elevator goes up and down the workpiece carrying arm will also go up and down.

At predetermined points along the machine the lift angle 30 is interrupted, as will be seen at 34 in Figure 1. In these positions there is a bridge member 36 overlapping adjacent ends of the interrupted lift angle 30 and mounted thereon is an angle bracket 38 slidably guided on a pair of spaced rods 40 that are carried in the brackets 42 and 44 attached to frame 10 of the processing machine.

Bracket 38 is connected, as by arm 46, with a chain 48 that extends around an upper sprocket 50 and a lower sprocket 52. Sprocket 52 is journaled for free rotation on the frame of the machine, while sprocket 50 is connected with a shaft 56, journaled in a bearing 54, through an over-running clutch 58 which permits the sprocket to turn freely on the shaft in one direction, but prevents relative movement therebetween in the opposite direction.

Shaft 56 has mounted thereon a gear 60 which meshes with a gear 62 on the output shaft of a

geared head motor 64. The over-running clutch 58 is better illustrated in Figure 3 and will be seen to comprise an outer cylindrical shell 66 forming a part of sprocket 50, the balls 68 within the shell, and the actuator cam 70 which is keyed to shaft 56. The over-running clutch is so arranged that when motor 64 is de-energized, thereby locking its output shaft, gears 62 and 60, and shaft 56 against rotation, the forward reach of chain 48 which is connected with arm 46 will be prevented from moving downwardly.

Because of this, whenever elevator 32 moves upwardly it will carry bridge 36 upwardly and thereby lift bracket 38 upwardly. During the time that the elevator is up, the movement of the conveyor, comprising conveyor chains 14 and 18 takes place so that one of the workpiece carrying arms 26 will be moved to a position where its roller 28 will be engaged by bracket 38. Thereafter, when the elevator moves down the said workpiece carrying arm will be supported in an upper position due to the fact that the forward reach of the chain is prevented from moving downwardly as explained above.

According to this invention a delayed set-down of the workpiece carrying arm is obtained by energizing motor 64 a predetermined length of time after the workpiece carrying arm moves into the position where its roller 28 is supported by bracket 38. In this manner a shortened treatment time is obtained.

As will be seen, the device can also be adjusted to hold the carrier arm in its elevated position so as to completely bypass a treatment station if so desired.

Turning now to the wiring diagram illustrated in Figure 4, there are two power lines L-1 and L-2 and connected therebetween is a contactor having a coil 80 that is in series with a normally open limit switch LS-1. The contactor has a blade 82 that establishes a holding circuit for coil 80 through a normally closed timer switch blade 83. The contactor also has a blade 84 which will close when the contactor is energized to energize the motor of timer T-1. Timer motor T-1 controls timer blades 83 and 85. Blade 85 is in series with motor 64 and normally closed limit switch LS-3 so that a predetermined time after timer motor T-1 is energized blade 85 will close and energize motor 64 thereby bringing about movement of chain 48 in a direction to lower the workpiece arm supported thereon.

Limit switch LS-1 as will be seen in Figure 5 is arranged for being selectively engaged by cam member 86 adjustably mounted on arm 26 so that as arm 26 approaches the position where it will be supported by bracket 38, it will engage limit switch LS-1 and initiate the timed cycle which will determine the length of time the arm is supported in its upper position.

A predetermined time after blade 85 closes and the chain 48 operates to set arm 36 down, blade 83 will be opened to de-energize the contactor which was closed by engagement of limit switch LS-1.

If a different timed period is desired, cam 86 is adjusted so as to strike limit switch LS-2 and under these circumstances a second contactor having a coil 88 is closed and brings about energization of a second timer T-2 that controls normally closed blade 90 in the holding circuit for the coil 88 and normally open blade 92 connected in parallel with blade 85 of timer T-1. The timers T-1 and T-2, being set for different intervals, it will be evident that adjustment of cam mem-

ber 86 will selectively determine the duration of the period that the arm 26 is held out of the bath at the treatment station. In this manner the duration of the treatment time on the workpiece is varied because the elevator and conveyor operate on a time cycle and the overall treatment of the workpieces reduced by the amount of time that it is held in an elevated position. It will also be evident that adjustment of member 86 so it will strike neither of limit switches LS-1 or LS-2 will cause the workpiece 49 to be held out of the treatment bath during a complete elevator cycle.

Due to the over-running clutch arrangement of Figure 3 it is not essential that motor 64 be de-energized as soon as the workpiece arm is set down but for reasons of economy limit switch LS-3 is provided in the circuit of Figure 4 as described and is so placed on frame 10 that a cam 94 on chain 48 will actuate the switch to de-energize the motor 64 as soon as the workpiece arm reaches its lowermost position.

Modification of Figure 6

Referring now to the modification shown in Figure 6, essentially the same sort of operation obtains except that instead of motor 64 and chain 48 there is provided a hydraulic arrangement for obtaining the delayed set-down of the carrier arm.

In Figure 6 the parts of the machine, carrier arm and elevator bear the same reference numerals as they do in Figures 1 through 5.

In Figure 6 the bracket 38, as before, is mounted on a block which slides on vertical rods 40 and attached to the rear of the block is a second block 100 to which is connected the upper end of piston rod 102 having a piston 104 at its lower end reciprocably mounted in stationary cylinder 106. The lower end of cylinder 106 is connected by conduit 108 with fluid reservoir 110 and the said conduit includes an electrically operated shut-off valve 112 that is normally closed and which will open upon energization of solenoid S-1, and an adjustable choke valve 114. The aforementioned valves are by-passed by conduit 116 including a check valve 118 opening from reservoir 110 to cylinder 106.

In operation, whenever elevator 32 moves upwardly it carries with it bracket 38 due to bridge member 36 as previously described. During upward movement of bracket 38 piston rod 102 and piston 104 are free to move upwardly in cylinder 106 because fluid will readily flow from reservoir 110 into the bottom end of the cylinder through conduit 116 and check valve 118. Thereafter, when the elevator moves downwardly, bracket 38 will be supported on the fluid entrapped in the lower end of cylinder 106 by check valve 118 and closed valve 112.

Valve 112 has its solenoid S-1 connected in a circuit such as shown in Figure 4 in the position occupied by motor 64 and, thus, a predetermined time after carrier arm 26 moves into position where its roller 28 is supported on bracket 38, solenoid S-1 will be energized and permit exhausting of fluid from cylinder 106, thereby permitting piston 104, piston rod 102, bracket 38, and carrier arm 26 to move downwardly. During downward movement of these parts, choke valve 114 is operable to limit the rate of descent to avoid damage of any of the machine parts or undue splashing of the bath.

A difference that might be pointed out between the first and second modifications is that in the

modification of Figures 1 through 5 a simple inversion of the operation could be obtained so that the carrier arm 26 could be lifted out of a solution by bracket 38 to terminate a treatment cycle ahead of the normal completion time, whereas in the arrangement of Figure 6 it is not possible to obtain an early lift-out but only a delayed set-down. Otherwise, in operation the modifications are quite similar.

Modification of Figures 7 through 9

In the modification of Figures 7 through 9 the essential difference over what is shown in Figures 1 through 5 is that the block which supports bracket 38 is divided into halves as at 120 and 122 so as to embrace rods 40. The splitting of the bracket permits the central part thereof to be hollowed out to receive a pair of worm wheels 124 which engage opposite sides of lead screw 126 suitably mounted at its opposite ends in brackets 128 carried by frame 10. At its upper end lead screw 126 has a worm wheel 130 adapted for being driven by a worm 132 on the shaft of motor 134.

Each worm wheel 124 is mounted in part 120 of the block that supports bracket 38 by means of an over-running clutch best illustrated in Figure 9. This clutch comprises the cam surfaces 136 in the block and the balls 138 adapted for wedging between these surfaces and the shaft 140 of the worm wheel. The over-running clutch is so arranged that the worm wheels will roll freely on the lead screw while the bracket is moving upwardly but will not turn in the block in the opposite direction. This permits upward movement of bracket 38 whenever the elevator goes up but requires that the lead screw be driven in order to lower the said bracket.

By the use of a circuit as shown in Figure 4, and wherein motor 134 replaces motor 64, a delayed set down of the bracket 38 can be obtained. It will be evident that the modification of Figures 7 through 9 is capable of operating in the same manner as the modification of Figures 1 through 5 in that a delay set-down can be obtained, or by an inversion of the actuating system an early lift out can also be obtained.

In connection with any of the modifications it will be apparent that a processing machine operating on a fixed cycle so far as conveyor and elevator movement is concerned can nevertheless be arranged for selective treatment of different batches of workpieces, merely by adjusting the switch actuating means on the arms that carry the said batches. In this manner, treatment baths can be bypassed and treatment time in other baths can be reduced a closely regulated amount, all in accordance with the exact treatment requirements of the workpieces on the various arms.

At the same time, the machine in general is standard and the optimum conditions of bath composition, bath temperature, current density, and other factors necessary for obtaining high quality results may be maintained.

Modification of Figures 10 through 12

In Figures 10 through 12 there is shown an arrangement constructed like the arrangement of Figures 1 through 5 except that the device of the instant modification is adapted for use as an early lift out device to terminate a treatment cycle ahead of its normal end point. Accordingly, the illustrated device operates entirely independently of the elevator of the machine and is driven in

both directions by its actuating motor. The devices are placed so as to align with the carrier arms in certain conveyed positions thereof, as for example, part way along a plating tank so the carrier arms to be lifted out by the device would traverse the first portion of the plating tank and then be lifted out of the tank and held in an elevated position during the remainder of the travel along the plating tank.

Referring now to Figures 10 and 11, the lift out member is indicated at 150 and will be seen to comprise a plate that is normally spring urged into position to engage the roller 28 of the carrier arm 26. The lift out member is connected with a chain 152 similarly to the member 38 of the modification of Figures 1 through 5. Chain 152 is supported on sprockets 154 and the upper thereof is keyed to shaft 156 adapted for being driven by reversible motor 158.

A limit switch LS-10 is positioned for being selectively engaged by adjustable cam 160 carried on arm 26 so that the lift out device can be made selectively operable or inoperable for different carrier arms.

Switch LS-10 is connected in circuit as shown in Figure 12 wherein it will be seen to be in series with a contactor coil 162. Coil 162 controls contact blade 164 that establishes a holding circuit for coil 162 through normally closed limit switch LS-12, and a blade 166 adapted for energizing motor 158 to run in a direction to move lift out member 150 upwardly.

Mounted on chain 152 is a cam 168 that is adapted for engaging and opening switch LS-12 when lift member 150 has reached its uppermost position. Opening of LS-12 de-energizes coil 162 and brings the lift out member to a halt inasmuch as motor 158 serves to hold shaft 156 stationary.

The lift out member 150 aligns with a holdout track 170 when in its uppermost position so that after the lift out member has elevated the associated carrier arm, the next movement of the conveyor of the machine will move the carrier arm onto track 170 to be supported thereby until it is again desired to commence treatment of the workpiece supported by the said carrier arm.

After the carrier arm has rolled off lift out member 150 the said member is caused to move downwardly to operative position by a limit switch LS-14 positioned to be engaged by the lift out arm after it has moved off lift out member 150. Limit switch LS-14, as will be seen in Figure 12, is connected with contactor coil 172. Coil 172 controls the blade 174 that establishes a holding circuit for the coil through normally closed limit switch LS-16, and a blade 176 that energizes motor 158 to run in a direction to move lift out member 150 downwardly. When the said member has reached the proper position, cam 168 engages and opens limit switch LS-16 thereby de-energizing coil 172 and motor 158 and thereby again halting shaft 156 so as stationarily to support lift out member 150.

In order to make certain that the lift out member does not come to rest on top of roller 28 of any of the carrier arms, it is constructed as illustrated and described so as to cam over the roller if necessary.

Modification of Figure 13

In Figure 13 the fluid operated device of Figure 6 is illustrated arranged for operation as an early lift out device. In Figure 13 the plunger 178 is connected to the lift out device and reciprocates

in cylinder 180. A pump 182 supplies fluid to a distributing valve 184 that is normally urged by spring 186 to bypass the pump discharge via conduit 188 to tank 190 and to connect conduit 192 leading to cylinder 180 to exhaust conduit 194. Energization of solenoid operator 196 of the valve will connect the pump discharge to conduit 192 thereby bringing about upward movement of plunger 178 and the lift out member connected thereto.

A check valve 198 permits free flow of fluid from pump 182 to the cylinder 180 while a choke valve 200 is connected parallel with the check valve and controls the rate of descent of plunger 178 when solenoid operator 196 is de-energized.

The solenoid operator 196 can be connected in the circuit of Figure 12 in the position of motor 158, except that the second contactor coil 172 and the elements associated therewith can be eliminated and limit switch LS-12 positioned in the location of limit switch LS-14 to be engaged and opened by the carrier arm after it is moved onto the hold out track by the conveyor.

Modification of Figure 14

In Figure 14 there is shown how a photocell circuit can be set up to replace the limit switches which have been employed in connection with the several modifications for controlling the operation of the various delayed set down and early lift out devices. In Figure 14, photocell 202 is normally illuminated by light source 204 and when so illuminated permits battery 206 to cause a current to flow through biasing resistor 208 in the direction indicated by arrow 210. This current places a negative bias on grid 212 of a relay tube which has relay coil 214 connected in its plate circuit. Relay 214 controls a switch 216 which is adapted for replacing any of the arm-operated limit switches previously referred to in connection with any of the modifications.

When the light beam falling on the photocell is interrupted by flag 218 adjustably carried on the carrier arm, the photocell current stops and battery 220 in the grid to cathode circuit then becomes effective for biasing the relay tube to discharge thereby closing switch 216. It will be apparent that the arrangement of Figure 14 could replace any of the arm-operated limit switches previously referred to and that the same selectivity of control would be obtained in every case.

It will be understood that this invention is susceptible to modification in order to adapt it to different usages and conditions, and, accordingly, it is desired to comprehend such modifications within this invention as may fall within the scope of the appended claims.

I claim:

1. In a processing machine having a workpiece supporting arm, a conveyor for moving the arm horizontally, and an elevator for moving the arm vertically relatively to the conveyor; a member positioned to engage the arm in one of its conveyed positions, means guiding said member for vertical movement, means for causing simultaneous upward movement of said member and arm with the elevator, means functioning independently of the elevator for supporting said member and arm in their elevated positions after the elevator has moved down, and control means for bringing about downward movement of said member and arm a predetermined time after the elevator has moved down.
2. In a processing machine having a workpiece supporting arm, a conveyor for moving the arm

horizontally, and an elevator for moving the arm vertically relatively to the conveyor; a member positioned to engage the arm in one of its conveyed positions, means for causing simultaneous upward movement of said member and arm with the elevator, means operable independently of the elevator to support the member and arm in their elevated positions after the elevator has moved down, and electrical means energizable for causing said supporting means to lower said member and arm a predetermined time after the elevator has moved down.

3. In a processing machine having a workpiece supporting arm, a conveyor for moving the arm horizontally, and an elevator for moving the arm vertically relatively to the conveyor; a member positioned to engage the arm in one of its conveyed positions, means for causing simultaneous upward movement of said member and arm with the elevator, means operable independently of the elevator to support the member and arm in their elevated positions after the elevator has moved down, electrical means energizable for causing said supporting means to lower said member and arm a predetermined time after the elevator has moved down, a control circuit for bringing about energization of said electrical means, and means actuated by said arm as it moves into said conveyed position for making said control circuit effective after a predetermined time delay.

4. In a processing machine having a workpiece supporting arm, a conveyor for moving the arm horizontally, and an elevator for moving the arm vertically relatively to the conveyor; a member positioned to engage the arm in one of its conveyed positions, means for causing simultaneous upward movement of said member and arm with the elevator, means operable independently of the elevator to support the member and arm in their elevated positions after the elevator has moved down, electrical means energizable for causing said supporting means to lower said member and arm a predetermined time after the elevator has moved down, a control circuit for bringing about energization of said electrical means, and a plurality of means adapted for selective actuation by said arm as it moves into said conveyed position and each operable for making said control circuit effective after a different predetermined time delay.

5. In a processing machine having a workpiece supporting arm, a conveyor for moving the arm horizontally, and an elevator for moving the arm vertically relatively to the conveyor; a member positioned to engage the arm in one of its conveyed positions, means for causing simultaneous upward movement of said member and arm with the elevator, means operable independently of the elevator to support the member and arm in their elevated positions after the elevator has moved down, electrical means energizable for causing said supporting means to lower said member and arm a predetermined time after the elevator has moved down, a control circuit for bringing about energization of said electrical means, a plurality of means adapted for selective actuation by said arm as it moves into said conveyed position and each operable for making said control circuit effective after a different predetermined time delay, and means for de-energizing said electrical means when the said member reaches its lowered position.

6. In a processing machine of the type described having a plurality of work stations, a plurality of work supporting devices, a conveyor

to move said devices from station to station, and an elevator for raising and lowering said devices relatively to the conveyor, said conveyor and elevator operating alternately so conveying takes place only while the elevator is in its up position; members at at least some of said stations adapted for engagement with said devices operable to support the said devices in elevated positions when the elevator goes down, and an independent control means for each member operable to bring about lowering movement thereof independently of the elevator a predetermined time after the elevator has gone down.

7. In a processing machine of the type described having a plurality of work stations, a plurality of work supporting devices, a conveyor to move said devices from station to station, and an elevator for raising and lowering said devices relatively to the conveyor, said conveyor and elevator operating alternately so conveying takes place only while the elevator is in its up position; members at at least some of said stations adapted for engagement with said devices operable to support the said devices in elevated positions when the elevator goes down, independent control means for each member operable to bring about lowering movement thereof independently of the elevator a predetermined time after the elevator has gone down, a control circuit for each said independent control means to bring about energization thereof, switch means for each circuit actuatable to determine the time the circuit will become effective, and means on said work supporting devices adjustable into position to engage at least one of said switch means or to bypass all of the said switch means.

8. In a processing machine having a workpiece supporting arm, a conveyor for moving the arm horizontally, and an elevator for moving the arm vertically on the conveyor; a member positioned to engage the arm in one of its conveyed positions, means for causing simultaneous upward movement of said member and elevator, an endless chain connected to said member and sprockets supporting said chain, a normally stationary shaft for one of the sprockets and a clutch between the shaft and said one sprocket permitting the aforesaid upward movement of the member but preventing downward movement thereof, and a motor energizable to drive said shaft in a direction to permit lowering of said member.

9. In a processing machine having a workpiece supporting arm, a conveyor for moving the arm horizontally, and an elevator for moving the arm vertically on the conveyor; a member positioned to engage the arm in one of its conveyed positions, means for causing simultaneous upward movement of said member and elevator, an endless chain connected to said member and sprockets supporting said chain, a normally stationary shaft for one of the sprockets and a clutch between the shaft and said one sprocket permitting the aforesaid upward movement of the member but preventing downward movement thereof, a motor energizable to drive the shaft in a direction to permit lowering of said member, and control means to bring about energization of said motor a predetermined time after the elevator has moved down.

10. In a processing machine having a workpiece supporting arm, a conveyor for moving the arm horizontally, and an elevator for moving the arm vertically on the conveyor; a member positioned to engage the arm in one of its con-

veyed positions, means for causing simultaneous upward movement of said member and elevator, an endless chain connected to said member and sprockets supporting said chain, a normally stationary shaft for one of the sprockets and a clutch between the shaft and said one sprocket permitting the aforesaid upward movement thereof, a motor energizable to drive the shaft in a direction to permit lowering of said member, a control circuit for bringing about energization of said motor, and means actuated by said arm as it moves into said conveyed position for making said control circuit effective after a predetermined time delay.

11. In a processing machine having a work-piece supporting arm, a conveyor for moving the arm horizontally, an elevator for moving the arm vertically on the conveyor; a member positioned to engage the arm in one of its conveyed positions, means for causing simultaneous upward movement of said member and elevator, an endless chain connected to said member and sprockets supporting said chain, a normally stationary shaft for one of the sprockets and a clutch between the shaft and said one sprocket permitting the aforesaid upward movement thereof, a motor energizable to drive the shaft in a direction to permit lowering of said member, a control circuit for bringing about energization of said motor, and a plurality of means adapted for selective actuation by said arm as it moves into said conveyed position and each operable to make said control circuit effective after a different predetermined time delay.

12. A method of treating workpieces in a processing machine which comprises the steps of, (a) supporting a plurality of workpieces in fixed horizontally spaced relation, (b) intermittently moving the workpieces in unison in one direction without changing the said spacing to convey them to a plurality of work stations, (c) reciprocating the workpieces in another direction at right angles to said one direction between intervals of movement thereof in the said one direction according to a fixed timed cycle to carry them into and out of the work stations but without changing their position in the said one direction, and (d) selectively reciprocating at least some of the workpieces according to individual cycles different from said fixed cycle and in the said other direction independently of the reciprocation of the others thereof while maintaining the same said spacing to vary the time of said some of the workpieces in treatment position in the work stations.

13. A method of treating workpieces in a processing machine which comprises the steps of, (a) independently supporting the workpieces at a fixed horizontal spacing, (b) intermittently moving the workpieces in unison according to a fixed cycle in one direction without changing the said spacing to convey them successively through a plurality of work stations, (c) and selectively independently reciprocating the workpieces according to individual cycles in another direction at right angles to said one direction while maintaining said fixed spacing during intervals of movement of the workpieces in the said one direction for carrying the workpieces into and out of treatment position in said work stations.

14. In a processing machine having a work-piece supporting arm, a conveyor for moving the arm horizontally, and an elevator for moving the arm vertically; the combination defined in claim 1 in which the means for supporting the member

in its elevated position include a vertical lead screw, an element on the member engaging the screw and movable along the screw by rotation of the latter, clutch means between the gear and member permitting upward movement of the member but preventing downward movement thereof along the screw, while the latter is at rest, a motor for driving the screw to move the member downward, and control means for effecting energization of the motor a predetermined time after the elevator goes down, the control means being adapted for selective operation in response to movement of the arm to one of its conveyed positions.

15. In a processing machine having a work-piece supporting arm, a conveyor for moving the arm horizontally, and an elevator for moving the arm vertically; the combination defined in claim 1, in which the means for supporting the member in its elevated position include a vertical lead screw, a pair of gears journaled on the member and engaging the screw, clutch means between the gears and member permitting upward movement of the member but preventing downward movement thereof along the screw, while the latter is at rest, a motor for driving the screw to move the member downward, and means under the selective control of said arm as it is moved into said one conveyed position for effecting energization of said motor a predetermined time after the elevator has gone down.

16. In a processing machine having a work-piece supporting arm, a conveyor for moving the arm horizontally, and an elevator for moving the arm vertically; the combination defined in claim 1, in which the means for supporting the member in its elevated position include a piston and cylinder, one of which is stationary and the other movable and connected to the member, whereby upward movement of the member causes fluid to be drawn into one end of the cylinder, means for entrapping the fluid in the cylinder to support the member elevated after the elevator has gone down, and means adapted for being made selectively effective by movement of said arm and operable, when effective, a predetermined time after the elevator has gone down to release the fluid from the cylinder.

17. In a processing machine having a work-piece supporting arm, a conveyor for moving the arm horizontally, and an elevator for moving the arm vertically; the combination defined in claim 1, in which the means for supporting the member in its elevated position include a piston and cylinder, one of which is stationary and the other movable and connected to the member, whereby upward movement of the member causes fluid to be drawn into one end of the cylinder, means for entrapping the fluid in the cylinder to support the member elevated after the elevator has gone down, and means adapted for being made selectively effective by movement of said arm and, when effective, operable a predetermined time after the elevator has gone down to release the fluid from the cylinder, said fluid releasing means including flow control means for regulating the rate of descent of the member.

18. In a processing machine having a work-piece supporting arm, a conveyor for moving the arm horizontally, and an elevator for moving the arm vertically; the combination defined in claim 1, in which the means for supporting the member in its elevated position include a piston and cylinder, one of which is stationary and the other movable and connected to the member,

13

whereby upward movement of the member causes fluid to be drawn into one end of the cylinder, means for entrapping the fluid in the cylinder to support the member elevated after the elevator has gone down, an electrically operated valve energizable to release fluid from the cylinder, a control circuit for bringing about energization of the valve, and means adapted for selective actuation by the arm as it moves to said conveyed position for making the control circuit 10 effective after a predetermined delay.
